UNITED STATES PATENT OFFICE.

LAWRENCE E. BIRKLAND, OF GRAETTINGER, IOWA.

POST-HOLE AUGER.

1,171,086.

Specification of Letters Patent.

Patented Feb. 8, 1916.

Application filed July 26, 1915. Serial No. 42,002.

To all whom it may concern:

Be it known that I, LAWRENCE E. BIRKLAND, a citizen of the United States, residing at Graettinger, in the county of Palo Alto and State of Iowa, have invented certain new and useful Improvements in Post-Hole Augers; and I do declare the following to be a full, clear, and exact description of the invention, such as will enable others skilled in the art to which it appertains to make and use the same.

This invention relates to new and useful improvements in post hole augers and more particularly to that class of post hole augers wherein the blade carrying portion or body is constructed of two parts, and the primary object of the invention is to provide a device of this character in which one of the parts is movable outward, whereby the dirt may be easily and quickly removed from the auger after the same has been withdrawn from the ground.

A further object of the invention is to provide a device of this character which is simple and durable in construction, inexpensive to manufacture, and one which will be very efficient in operation.

With these and numerous other objects in view, my invention consists in the certain novel features of construction, combination and arrangement of parts which will be hereinafter referred to and more particularly pointed out in the specification and claims.

In the accompanying drawings: Figure 1 is a side elevation of my improved post hole auger showing one of the parts partly in section; Fig. 2 is a horizontal section taken on the line 2—2 of Fig. 1; and Fig. 3 is a vertical transverse section taken on the line 3—3 of Fig. 1.

In describing my invention, I shall refer to the accompanying drawings in which similar reference characters designate corresponding parts throughout the several views and in which the numeral 1 designates the handle or pole, to which is secured at its upper end a transversely extending operating handle 2. To the lower end of the handle 1 is secured as shown at 3, a T-shaped cross head 4 to which is adapted to

be secured the dirt drilling and lifting portion of the auger. To one end of the cross head 4 of this device, which is designated by the numeral 5, is fixedly secured a blade 6 by means of securing strips on the inner and outer surfaces of the same which are designated by the numeral 7 and secure the two above mentioned parts together by any desired fastening means for instance as shown at 8. The lower end of this fixed blade 6 has a laterally curved auger bit 9 formed thereon, which may be of the ordinary type used in post hole augers of this character. The other end of the cross head 4 is bifurcated as shown at 10, and has secured or fulcrumed between said bifurcated portions a shank 11 to which is connected at its lower end, a blade 12. This blade 12 is securely fastened to the lower end of the shank 11 by fastening means 13 which are clearly shown in Fig. 3 of the drawing. The lower end of the blade 12 has formed thereon a corresponding laterally curved auger bit 14 which is adapted to coöperate with the auger bit of the opposite blade 6 to operate this device. The inward movement of the movable blade 13 is limited by the lower end of the sloping portion 15 which is formed between the bifurcated portions of the end 10 of the cross head 4.

Disposed adjacent the handle 1, is a lever 17, having formed therein intermediate of its ends, a longitudinally extending arcuate slot 16. This slot 16 has its upper end 21 extending straight, or transversely across the said lever for a short distance, so that the inner shoulder which is designated by the numeral 22 of the said slot will form a lock or stop as will be hereinafter more fully described. This lever 17 is adapted to be pivotally and slidably mounted with respect to the handle 1 of the auger by means of a laterally projecting pin or bolt 18, having an enlarged head on its outer end, and which is adapted to project through the slot to hold the lever with respect to the handle. The lower end of the lever 17 is curved as shown at 19 and is fulcrumed at its outer extremity to the upper extremity of the shank 11 at 20. The upper end of

said lever is curved inward slightly as shown at 23, and has a gripping handle formed thereon. The object of this curve on the upper end of the lever 17 is to move the same inward so that when the auger is inserted or bored into the earth, the said end of the lever will be positioned in from the hole formed thereby, so that it will not strike the earth at any point.

10 When the parts of this device are assembled as shown at Fig. 1 of the drawings, it will be noted that the blades 6 and 12 are disposed in substantially parallel relation with respect to each other, so that upon insertion and contact with the ground, and upon rotation of the handle 1, the said blades will bore into the ground and gather a certain amount of earth in the space therebetween. During this operation, the 15 movable blade 12 will be held firmly and securely in position, and immovable, owing to the fact that the pin or bolt 18 which connects the operating lever 17 to the handle 1 is positioned in the straight portion 21 of the slot 16 in said lever, and consequently the lever 17 will not be able to move longitudinally, which is the only movement which will be imparted thereto through the blade 12. This straight portion 21 and 20 shoulder 22 of the slot 16 prevent any movement of the lever 17 except transversely thereacross when the pin or bolt 18 is positioned therein; hence when the movable blade 12 is in operative position as shown 25 in Fig. 1 of the drawings, the same will be firmly and securely held therein, and would be only released therefrom by a transverse movement of the gripping lever.

When it is desired to remove the earth 40 which is choked or packed between the said blades, after the auger has been operated, the auger is removed from the ground, and the lever 17 is grasped at its outer end 23 and moved transversely across and then upwardly, according to the direction allowed by the coaction between the pin 18 and the slot 16. This operation will shift the lever upwardly owing to the said connection with the handle 1, and likewise bring the 45 lower end of the same inwardly, and as the said lower end is fulcrumed to the upper extremity of the shank 11 of the blade 12, the said blade will be moved outwardly from its normal position parallel with the 50 blade 6. This is due to the co-operative action because of the fulcrum 11', on the end 10 of the cross head 4, and the shank 11. When the movable blade 12 is in the aforesaid position, which is clearly illustrated 55 by dotted lines in Fig. 1 of the drawings, it will be obvious that the dirt will be released from between the blades so that when the lever is swung back to its original position, the blades will consequently assume

their normal parallel position, and the 65 auger will be again ready for use.

From the foregoing description of the construction of my improved device, the manner of applying the same to use, and the operation thereof will be readily understood, and it will be seen that I have provided a simple, inexpensive and efficient means for carrying out the objects of this invention.

I claim:

1. In a post hole auger, the combination of a handle, a relatively fixed blade carried by the lower end of said handle and having a laterally curved auger bit thereon, a relatively movable blade having a shank fulcrumed on said handle and a laterally curved bit adapted for coaction with the auger on the fixed blade, a lever fulcrumed to the shank of said movable blade, and said lever pivotally and slidably movable on the 85 handle.

2. In a post hole auger, the combination of a handle having a cross head at its lower end, a blade fixedly secured at its upper end to one end of said cross head and having a laterally curved bit on its lower end, an additional blade having an upwardly projecting shank at its upper end fulcrumed to the opposite end of said cross head, a laterally curved bit on the lower end of said 95 blade, a lever having a curved lower end fulcrumed to the upper extremity of said shank, said lever having a longitudinally extending arcuate slot therein intermediate its ends, and a laterally projecting pin on 100 the said handle projecting through said slot and slidably therein.

3. In a post hole auger, the combination of a handle, a relatively fixed blade carried by the lower end of said handle and having 105 a laterally curved auger bit thereon, a relatively movable blade having a shank fulcrumed on said handle and a laterally curved bit adapted for coaction with the auger on the fixed blade, a lever pivotally 110 and slidably movable on the handle fulcrumed to the shank of said movable blade, and coacting means at said connection between the lever and handle to lock the movable blade when in operative position.

4. In a post hole auger, the combination with a handle having a cross head at its lower end, a blade fixedly secured at its upper end to one end of said cross head and having a laterally curved bit on its lower end, an additional blade having an upwardly projecting shank at its upper end fulcrumed to the opposite end of said cross head, a laterally curved bit on the lower end of said blade, a laterally projecting pin in 125 said handle, a lever having a curved lower end fulcrumed at the upper extremity of the said shank, and said lever having there-

in a longitudinally extending arcuate slot adapted to engage said pin, the upper end portion of said slot in which the pin is disposed when the movable blade is in operative position being straight to prevent any longitudinal movement of the lever when the pin is in said position and to lock the movable blade thereby.

In testimony whereof I have hereunto set my hand in presence of two subscribing 10 witnesses.

LAWRENCE E. BIRKLAND.
